UNITED STATES PATENT OFFICE.

MILTON S. DUNKELBERGER, OF DAYTON, OHIO.

TOY DUMP CAR AND COUPLING.

Application filed March 15, 1923. Serial No. 625,407.

To all whom it may concern:

Be it known that I, MILTON S. DUNKELBERGER, a citizen of the United States, residing at Dayton, in the county of Montgomery and State of Ohio, have invented certain new and useful Improvements in Toy Dump Cars and Couplings, of which the following is a specification.

This invention relates to new and useful improvements in toy dump cars and couplings, and has particular reference to a toy car whose body may be tipped by pulling upon a chain, cable or like means.

It is the principal object of my invention to provide a toy dump car having a tiltable body portion with balancing and locking means for normally holding it in a horizontal position to receive a load.

It is another object of my invention to provide means such as a chain that may be pulled from a distance to disengage the locking means from the body to permit the latter to be automatically tipped for the purpose of discharging its load.

It is still another object of my invention to provide simple, efficient and readily operated means for coupling the dump car to another toy car or engine.

Other important and incidental objects will be brought out in the following specification and particularly set forth in the subjoined claims.

In the accompanying drawings illustrating one form of embodiment of my invention, Figure 1 is a side elevational view of my toy dump car showing the tiltable body in a horizontal load-receiving position; said view also showing a side elevation of the rear end of another car to which the first car is coupled by my improved coupling means. Figure 2 is a front view of my improved dump car, showing its tiltable body locked in a horizontal position. Figure 3 is a side elevational view of my toy dump car showing the tiltable body in a vertical dumping position, said view also showing the second car uncoupled from the first. Figure 4 is a top plan view of the locking device. Figure 5 is a side elevational view of the female coupling member. And Figure 6 is a side elevational view of the different parts of the male coupling member.

Throughout the specification and drawings, similar reference characters denote corresponding parts.

Referring to the accompanying drawings for a detailed description of the form of embodiment of my invention illustrated therein, the numeral 1 designates a toy car frame which preferably comprises a light, durable casting which is supported by wheels 2, 2. Projecting upwardly from the front and rear portions of the casting 1 are integral supporting standards 3, 3. Secured between the tops of these standards is a shaft 4. (See Figures 1, 2 and 3.)

At its top each standard has an inwardly projecting boss portion 5. Pivotedly secured upon the front end of the shaft 4 behind the boss 5 of the front standard 3, is a lever arm 6 which projects a greater distance below the shaft than above it. Pivotally mounted on the other end of the shaft 4 behind the boss 5 of the rear standard 3 is an arm 7 which projects above the shaft to support, with the upper end of the arm 6, a dump or tiltable body 8 which is suitably formed from sheet metal in tray shape to receive grain, sand or a like substance.

For the purpose of normally maintaining the body 8 in a horizontal position, there is suitably secured to the lower end of the lever arm 6 a balancing weight 9. (See Figure 1.) In order to lock the body in this position, the following means are provided. Referring to Figures 1, 2 and 3, there is hingedly secured to a shaft 10 supported in the front portion of the frame 1, a bell-crank lever 11. At its upper end this lever has an inwardly-extending yoke portion 12 which is adapted to straddle the front standard 3 and the lower end of the lever arm 6 to lock the latter in a vertical position, thereby to maintain the body 8 in a horizontal position for the purpose of receiving and holding a load. (See Figures 1 and 4.)

Secured to the upper end of the bell-crank lever 11 is an apertured ear 13 which receives one end of a chain 14. When a pull is exerted upon this chain it will draw the yoke portion 12 of the lever 11 free from the lever arm 6 as shown in Figure 3, to permit the weight of the load in the body 8 to tip it to a vertical position as shown in said figure, for the purpose of discharging its load. At its lower end the bell-crank lever 11 terminates in an inwardly-projecting tongue part 15 which is adapted to engage the arched portion of the front standard 3 when the upper portion of the

bell-crank lever is pulled outwardly, to limit its outward movement.

As soon as the load is discharged by the tiltable body 8, the gravitational force exerted by the weight 9 on the lower end of the lever arm 6 will draw the body 8 back to its horizontal position preparatory to being again locked in that state by the yoke end of the bell-crank lever 11. It is thus seen that by pulling upon the chain 14, a child can withdraw the yoke end of the bell-crank lever free from the lever arm 6, whereupon the body 8 will automatically dump its load and thereafter automatically return to its horizontal position. If desired, the upper end of the chain 14 may be attached to a hook 16 secured to the dump body 8 as shown in Figure 2, when the car is not to be dumped.

For the purpose of coupling the dump car just described to another car 17, the following means are provided. Projecting outwardly from each end of the casting 1 is a female coupling member 18 which has a top concave portion 19. Secured to the rear end of the car 17 is an outwardly-projecting member 20 to which there is pivotally attached by a pin 21, a hook piece 22 having an inwardly curved nose portion 23 at its lower end for engagement in the concave portion 19 of the female coupling member 18. Hingedly secured by a pin 24 to the member 20 behind the hook piece 22 is a locking or stop member 25. At its rear end this member has an extension 26 which is adapted to limit the forward movement of the upper end of the hook piece 22. Therefore, when the nose portion 23 of the hook piece 22 is within the concave portion 19 of the coupling member 18, and the stop member 25 is in a horizontal position as shown in Figures 1 and 6, said hook piece will be maintained in connection with said coupling member by the engagement of the rear straight end of the hook piece with the extension 26 of the stop member. (See Figure 1.)

For the purpose of elevating the rear end of the stop member 25 so that the upper end of the hook piece 22 may move a sufficient distance to permit its nose portion 23 to clear the end of the coupling member 18, the following means are provided. Referring to Figure 6 there is fixedly secured to a shaft 27 supported in the rear end of the car 17, an arm 28. When the shaft is turned by a crank 29 fast on its outer end, the arm 28 will engage a boss 30 on the front reduced end of the stop member 25 to elevate its rear extension 26. Now, when the car 17 moves forwardly, the curved nose portion 23 of the hook piece is free to slide out of the recessed portion 19 of the coupling member 18, since the rearward movement of the upper end of the hook piece will not be opposed

when the extension 26 on the stop member 25 is raised above it as shown in Figure 3. Furthermore, when the extension 26 of said stop member is in an elevated position, the cars are free to be coupled, since the curved nose portion 23 of the hook piece will readily slide over the end of the coupling member 18 to enter its recessed portion 19 when it is forced against said end of the coupling member. The nose portion of the hook piece may then be firmly held in the recessed portion of the coupling member 18 by returning the stop piece 25 to its horizontal position through the instrumentality of the crank 29 or other means. It is thus seen that I have provided simple and easily operated means for coupling two cars together.

For the purpose of dumping one car when the other car is pulled away from it, I have provided on the rear end of the car 17 an upwardly projecting member 31 to which there is secured a hook 32 to receive the free end of the chain 14. Accordingly when the dump car is uncoupled from the car 17 and the latter is drawn forwardly, it will exert a sufficient pull upon the chain 14 to cause the latter to draw the yoke portion 12 of the bell-crank lever 11 on the dump car, free from the lever arm 6, whereupon the body 8 of the dump car will be permitted to tilt for the purpose of discharging its load, as before described.

I do not wish to be limited to the details of construction and arrangement herein shown and described, and any changes or modifications may be made therein within the scope of the subjoined claims.

Having described my invention, I claim:

1. A toy dump car comprising a frame and supporting wheels therefor, supporting members projecting upwardly from the front and rear ends of the frame, a shaft supported by said members, arms mounted on said shaft and projecting above it, a dump body supported by said arms, and pivotal locking means carried by said frame to grip one of said arms to hold the dump body in a horizontal position, and free to be pulled from said arm to permit said body to tilt to an inclined position.

2. A toy dump car comprising a frame and supporting wheels therefor, supporting members projecting upwardly from the front and rear ends of said frame, a shaft supported by said members, arms mounted on said shaft and projecting above it, one of said arms having a balancing portion projecting below said shaft, a dump body supported by the upper ends of said arms, and pivotal locking means carried by said frame to grip the downwardly projecting balancing arm, and free to be pulled outwardly from said arm to permit said body to tilt to an inclined position.

3. A toy dump car comprising a frame

and supporting wheels therefor, supporting members projecting upwardly from the front and rear ends of said frame, a shaft supported by said members, arms mounted 5 on said shaft and projecting above it, one of said arms having a portion projecting below said shaft, a weight on the lower end of the projecting portion of said arm, a dump body supported by the upper ends of 10 said arms, a lever pivotally secured in said frame in front of the weighted arm, a yoke

on said lever, adapted to grip the weighted arm to hold the dump body in a horizontal position, and means for pulling said lever outwardly to disengage its yoke portion ¹⁵ from said weighted arm to permit said body to tilt to an inclined position.

In testimony whereof I have hereunto set my hand this 13th day of March, 1928.

MILTON S. DUNKELBERGER.

Witness:

HOWARD S. SMITH.
